FRACTURING FORMATIONS IN WELLS

John Dewey Chesnut, Newport Beach, Calif., assignor, by mesne assignments, to Aerojet-General Corporation, Cincinnati, Ohio, a corporation of Ohio

Application December 29, 1952, Serial No. 328,408

8 Claims. (Cl. 102—23)

This invention relates to the treatment of oil and gas wells. More particularly, the invention relates to a method for increasing the permeability of the oil producing zones so that an increase in the rate of oil production can be obtained.

Heretofore it has been the practice to attempt to increase the productivity of oil and gas wells by any one of several methods, with varying success. Among the established methods are: (1) shooting with nitroglycerine, (2) acidizing, and (3) formation fracturing by the application of hydraulic pressure to the formation.

Shooting with nitroglycerine is a dangerous method owing to the very great sensitivity of nitroglycerine to shock and/or temperature changes. The usual method of operation is to lower a charge of nitroglycerine into the well in a container and to detonate the nitroglycerine while in the container. The resulting explosion may enlarge the well bore at the area of explosion and may result in some fracturing of the formation in some instances. On the other hand, the force of the explosion within the bore hole tends to compact the formation, thus reducing its permeability to the flow of oil. Nitro shooting also creates a considerable quantity of debris in the bore of the well, which debris must subsequently be removed by bailing. This latter operation may consume several weeks of time at a cost of many thousands of dollars. In many instances nitro shooting is ineffective in increasing the production from the well or not sufficiently effective to warrant the expense of the job.

Acidizing, by treatment of calcareous formations with hydrochloric acid, is very effective in limestone or other formations which are soluble in hydrochloric acid but is not effective on sandstones or other non-calcareous formations. Acidizing has an advantage over nitro shooting in that the acid can be forced, by pressure, into the oil producing formation for a considerable distance, thus providing a greatly increased drainage area as well as an increase in permeability.

Formation fracturing, by the application of high hydraulic pressure to oil producing formations in order to crack or fracture the formations, thereby increasing their permeability, is a relatively new method which has met with commercial success in certain types of formations such as the Sprayberry sand found in certain areas in West Texas. The effectiveness of formation fracturing is limited by the capacity of the pumping equipment and by the tendency of the high pressure injection fluid to follow the open channels of least resistance instead of opening up new channels.

The present invention is directed toward an improved method of increasing the permeability of oil producing formations by first injecting into the formation a liquid explosive which is sufficiently shock-insensitive to withstand injection pressures as high as 10,000 p.s.i., or higher, and well temperatures up to 350° F., or higher, and second, detonating the liquid explosive in situ in the formation.

It has been found that a liquid explosive having the

2

desired characteristics can be made by sensitizing mononitromethane (CH_3NO_2) by adding a small percentage of an amine or mixture of amines sufficiently basic to form salts with a weak acid, either organic or inorganic.

5 Specific examples of such sensitizers are aniline, diethylamine or morpholine. The percent of sensitizer to be used is not critical and can be varied from one percent by volume to as much as forty percent by volume but is generally on the order of two percent to three percent. 10 Such a sensitized nitromethane is disclosed and claimed in the copending application of Edgar A. Laurence, Serial No. 605,747, filed July 18, 1945, and assigned to the same assignee as the present application.

The sensitized mixture can be detonated by means of 15 high velocity detonators such as some commercial blasting caps or "Primacord" (pentaerythritoltetranitrate).

The sensitized nitromethane is relatively shock insensitive and is not easily detonated by accidental means. A 2 kg. weight dropped 15 cm. resulting in an impact 20 force of 30 kg. cm. will detonate nitroglycerine, whereas a 4 kg. weight dropped 125 cm. resulting in an impact force of 500 kg. cm. failed to detonate sensitized nitromethane. A pressure increase on the order of 35,000 lbs. per second is necessary to cause detonation at atmospheric temperatures. At higher temperatures a lesser rate 25 of pressure increase may cause detonation. No detonation was caused by slowly increasing the pressure from zero p.s.i. gage to 10,000 p.s.i. gage while maintaining a temperature of 350° F. The sensitized nitromethane was 30 subsequently successfully detonated under these conditions of high pressure and high temperature.

The sensitized nitromethane has a specific gravity of 35 approximately 1,139 and weighs 71.25 lbs per cu. ft. Its boiling point is 101.9° C. (215.4° F.) It is only slightly soluble in water (9.5%), while the solubility of water in nitromethane is only 2.2%. These solubilities hold true for salt water (3% sodium chloride) as well as fresh water.

40 The sensitized nitromethane is not visibly miscible with crude petroleum oils. If agitated it will form a suspension which will settle out upon standing for a few minutes.

Sensitized nitromethane, when detonated, has a velocity 45 which is comparable to other high explosives, such as nitroglycerine or TNT (trinitro-toluene). On the other hand, the force exerted by sensitized nitromethane when detonated is considerably greater than that of unsensitized nitromethane, and is comparable with other high explosives such as nitroglycerine or TNT.

50 Sensitized nitromethane is stable at normal ambient temperatures and pressures. Its sensitivity to shock remains substantially unchanged by storage in black iron drums, tin cans, or glass jars for periods of at least one year and probably much longer.

55 Freezing of sensitized nitromethane decreases its shock sensitivity, but upon melting, the shock sensitivity of the material is substantially the same as it was before freezing.

Sensitized nitromethane can be transported with safety 60 but since it is a simple matter to sensitize it, this can usually be done at the job. Thus the transportation may involve no "explosive" material but only two slightly "inflammable" materials, for which the usual precautions should be observed.

65 Sensitized nitromethane is not toxic when placed in contact with human skin, and produces no permanent injurious effects.

The products of combustion are principally carbon monoxide, carbon dioxide and water.

70 Having described the nature and characteristics of the liquid explosive, the following description is given

for its use for fracturing oil well formations as illustrated in the drawings, wherein,

Fig. 1 is a vertical cross section of an oil well during the step of pumping the liquid explosive into the bore of the well;

Fig. 2 shows the well of Fig. 1 during the step of forcing the liquid explosive into the oil-producing formation.

Fig. 3 shows the well of Figs. 1 and 2 with the detonator in place, ready to be fired.

Figs. 4 and 5 show an alternative arrangement of the method shown in Figs. 1 to 3 wherein the bore of the well contains a filler to reduce the quantity of explosive in the bore hole.

Figs. 6 and 7 show the lower end of a string of tubing closed at its lower end by a rupturable diaphragm as employed in another method of operation wherein no pump pressure is employed;

Figs. 8 and 9 show a pressurizable dump bailer and packer for injecting the liquid explosive under pressure without the use of tubing.

Referring to Figs. 1, 2 and 3, there is illustrated one embodiment of a "pumping method" for injecting liquid explosive into a well formation and detonating the explosive in situ. A well casing 1 is shown cemented in place as indicated at 2 with its lower end above the oil producing formation 3 which is shown as being at the lower end of the well. A string of oil well tubing 4 extends from the top of the well to a point near the bottom of the well. An expandable packer 6 is attached to the lower end of the tubing 4. Below the packer and attached thereto is a length of perforated pipe 7, commonly called a "stinger." The upper end of the tubing 4 is connected to the discharge line 8 of a conventional pump truck having a high pressure pump 9 driven by an engine 10 and having a liquid storage tank 11 to receive liquid explosive.

If the nitromethane has been sensitized previously it is taken from the tank 11 by the pump 9 and forced through the tubing 4 to the bottom of the well as indicated at 5. Since the sensitized nitromethane is heavier than oil or water it will displace any such well fluids 13 upwardly until the top surface 14 of the liquid explosive is raised to the approximate top of the formation to be fractured. The tubing 4 is then raised until the packer 6 is within the lower end of the well casing 1, as shown in Fig. 2. The packer 6 may be of any well known type, expandable either mechanically or by applied hydraulic pressure, to seal off the lower section of the well from the upper section thereof. A liquid of less specific gravity than the liquid explosive and non-miscible therewith (such as petroleum oil) is pumped downwardly through the tubing 4 until most of the liquid explosive has been forced into the pores, cracks and fissures 15, of the oil producing formation. It is well known that if a sufficiently high injection pressure is applied, the overburden can be lifted and the formation can be cracked, usually along bedding planes. Such methods are usually referred to as hydraulic formation fracturing. The effectiveness of such hydraulic formation fracturing methods is limited to a relatively small area surrounding the bore of well and in many instances is wholly ineffective in increasing the area of the drainage channels leading from the oil producing formation to the bore of the well.

After the liquid explosive has been forced into the oil producing formation, while leaving the bore hole full of liquid explosive 5, as shown in Fig. 2, the packer 6 is collapsed and is withdrawn from the well along with the tubing 4. If the well pressures are balanced the fluid interface 17 between the liquid explosive 5 and the well fluid 13 will remain stationary, as shown in Fig. 3.

Various means can be used to detonate the explosive liquid 5. Fig. 3 illustrates one such means comprising

an electric wire line hoist truck 18 having an insulated conductor cable 19 on the lower end of which is a detonator or series of detonators 20 which are immersed in the liquid explosive 5 in the bore of the well throughout the formation which is to be fractured. When the electric circuit is closed by the operator of the truck 18 the detonators 20 are fired, thereby detonating the liquid explosive 5 not only in the well bore but also laterally into the pores, cracks and fissures 15 in the formation. The resulting explosion tends to form new cracks and fissures and to connect up existing cracks and fissures so that the drainage area in communication with the well bore is greatly increased, thus permitting an increase in the rate of flow of oil from the formation into the bore of the well.

An explosion once initiated in a body of sensitized nitromethane tends to travel throughout the body of liquid and throughout those pores, cracks and fissures which contain a continuous body of liquid explosive. The force exerted by the explosion is very great and is sufficient to enlarge the pores, cracks and fissures for as great a distance from the bore of the well as the liquid explosive has traveled while maintaining a continuous liquid phase.

If it is desired to sensitize the nitromethane at the well, so that it is not necessary to transport sensitized nitromethane to the well, this can be done by injecting the sensitizer into the nitromethane in the tank 11 (Fig. 1) or, preferably, into the stream of nitromethane discharged by the pump 9. In the latter case a liquid injector 22, fed from a supply tank 23, is interposed in the pipe 8 leading from the pump 9 to the tubing 4. A by-pass 24 can be provided around the injector 22, if desired.

If the bore of the well is of large diameter or if the thickness of the formation to be fractured is very great it may not be desirable to have the entire bore hole throughout the producing formation filled with explosive, particularly since such explosive is not very effective in increasing the area of the pores, cracks and fissures at a distance from the bore hole. In this event the stinger 7a (Fig. 4) below the packer 6 can be made of a frangible material, such as aluminum, magnesium or the like, and can be made long enough to extend substantially throughout the zone to be fractured. After the tubing 4, packer 6 and stinger 7a have been run into the well and before the packer 6 has been expanded, the well bore surrounding the stinger 7a can be filled with small pieces of solid material, such as marbles 25, which displace a large portion of the liquid explosive which would otherwise fill the bore of the well. After the explosive has been detonated the tail pipe 7a will have been disintegrated along with part of the marbles 25. The residue can be left in the well to function as a gravel pack or it can be removed by bailing or drilling.

A similar result could be obtained by making the stinger 7a with a large diameter, practically filling the bore hole except for running clearance, and filling the interior of the stinger with marbles or the like (not shown).

If the oil producing formations of the well are very porous and if there is insufficient well pressure to maintain a static fluid level at the top of the producing formation, the pumping method shown in Figs. 1 to 3 can not be used. In this event the desired result can be obtained by placing a rupturable diaphragm 27 (Fig. 6) at the discharge end of the stinger 7b secured in place by the discharge nozzle 28. The well tubing can be run into the well dry and subsequently filled with explosive liquid from the top of the well. The disc 27 can be ruptured as indicated in Fig. 7 either by the weight of the liquid in the well tubing or by applied pump pressure, allowing the liquid explosive to drain into the well. A detonator 29 can be placed on top of the column of liquid explosive and can be detonated when the top of

the column of explosive reaches the top of the stinger 7b. Detonation can be initiated by means of a pressure increase, a time bomb or by an electric detonator.

Still another method of performing the present process is illustrated in Figs. 8 and 9 wherein the liquid explosive 13a is lowered into the well 30 in a dump bailer 31 on the lower end of an insulated electric cable 32 attached to a hoist (not shown) at the top of the well. Above the dump bailer 31 and attached thereto is a steel or other metal cylinder 34, perforated as indicated at 35 and serving as a combustion chamber 36 for a grain of solid propellant 37. An igniter 38 at the top of the propellant grain 37 is connected to the leads 39 from the electric cable 32. Surrounding the perforated cylinder 34 and covering the perforations 35 is a heavy walled rubber sleeve 41, fastened at both ends by clamp rings 42. The propellant grain 37 is supported on a disc 43 having one or more perforations 44 therethrough serving as outlets for the gas generated in the combustion chamber 36. The lower end of the dump bailer 31 is provided with discharge ports 46 which are normally closed by suitable means such as a rupturable disc 47. If desired, a movable plug (or free floating piston) 50 can be placed on top of the liquid explosive 13a to protect it from contact with the heat or flame from the burning propellant 37.

When the electric circuit through the insulated line 32 is closed by the operator at the top of the well the igniter 38 is ignited and, in turn, ignites the upper end of the propellant grain 37.

The propellant grain 37 is preferably an end-burning grain coated with a suitable restriction 48 on the sides and bottom thereof to prevent burning except from the top down, as indicated in Fig. 9. The outside diameter of the propellant grain 37 is preferably made somewhat smaller than the inside diameter of the combustion chamber 36 so that gases generated by the burning of the propellant from its upper end can travel downwardly around the propellant grain and out through the perforations 44 in the supporting disc 43.

Owing to the confinement of the hot gases in combustion chamber 36 by the imperforate diaphragm 47 a pressure is build up within the combustion chamber 36, bailer 31 and sleeve 41 with the result that the sleeve 41 is first expanded tightly against the wall 49 of the well bore or well casing, as shown in Fig. 9. As the pressure continues to build up, the diaphragm 47 is ruptured and the liquid explosive is forced into the bore hole and into the formation by the expanded packer 41 which prevents the liquid explosive from migrating up the bore hole and the explosive is thereby forced into the formation.

When the propellant 37 has been completely burned, the temperature within the combustion chamber and dump bailer drops from a high of 1500-3500° F. to normal well temperature of 100-350° F. with a resultant pressure decrease, permitting the packer 41 to collapse so that the tool can be withdrawn from the well.

Following this operation a detonator such as is illustrated in Fig. 3 is lowered into the well, into the body 60

of liquid explosive remaining in the bore of the well and is detonated.

The term solid propellant, as used herein, means any of the so-called slow-burning solid propellants such as are commonly used in rockets or jet assistance take-off units for airplanes. The term "slow-burning" as used herein means that the burning rate, for an end-burning grain, is on the order of .05" per second at pressures up to approximately 1,000 p.s.i.

The term "sensitized nitromethane," as used herein, means mononitromethane, either pure or commercial grade, to which has been added a small percentage of an amine or mixture of amines sufficiently basic to form salts with a weak acid, as hereinabove set forth. The percentage of sensitizer can be varied in any practical amount but satisfactory results are obtained with two to three percent, by volume, of nitromethane.

The term "sensitized" as used herein, means that the shock sensitivity of the nitromethane has been increased to such a degree that the nitromethane can be detonated readily by means of common, high velocity, detonators such as "Primacord," either pentaerythritoltetranitrate or cyclotrimethylenetrinitramine.

While the foregoing specification and drawings illustrate three different methods of performing the invention herein described, it is to be understood that the invention is not necessarily limited to these three embodiments but is of the scope defined by the appended claims.

I claim:

1. A method of increasing the productivity of a formation penetrated by a well comprising the steps of introducing into the well a liquid explosive comprising sensitized nitromethane, causing said sensitized nitromethane to enter the pores, cracks and fissures in said formation and detonating said sensitized nitromethane in situ in said formation.
2. A method as defined in claim 1 in which pressure is applied to the sensitized nitromethane after it has been introduced into the well to force said sensitized nitromethane into the formation.
3. A method as defined in claim 1 in which mononitromethane is sensitized with an organic amine.
4. A method as defined in claim 1 in which mononitromethane is sensitized with diethylamine.
5. A method as defined in claim 1 in which mononitromethane is sensitized with aniline.
6. A method as defined in claim 1 in which mononitromethane is sensitized with morpholine.
7. A method as defined in claim 1 in which mononitromethane is sensitized with an aliphatic amine.
8. A method as defined in claim 1 in which mononitromethane is sensitized by a mixture of amines selected from the group consisting of diethylamine, aniline and morpholine.
